SEWING MACHINE BOBBIN-CASE

John D. Karle, Roselle Park, N. J., assignor to
The Singer Manufacturing Company, Elizabeth, N. J., a corporation of New Jersey

Application July 13, 1939, Serial No. 284,181

10 Claims. (Cl. 112—231)

This invention relates to sewing machine bobbin-cases, more particularly of the two-part type forming the subject of my copending U. S. patent application, Serial No. 263,318, filed Mar. 22, 1939.

5 In the two-part bobbin-case disclosed in my said copending application there is a latch-lever which has near its free end a lateral extension formed with a rib adapted to snap under a keeper-spring to retain the latch-lever in closed position.

10 The present invention has for an object the elimination of the keeper-spring and the lateral keeper extension on the latch-lever. A further object of the invention is to provide the latch-lever with means to close it and retain it closed, 15 said means being so contrived as not to encroach upon the bobbin cavity or impede the passage of needle-loops exteriorly over the bobbin-case.

With the above and other objects in view, as will hereinafter appear, the invention comprises 20 the devices, combinations, and arrangements of parts hereinafter set forth and illustrated in the accompanying drawing of a preferred embodiment of the invention, from which the several features of the invention and the advantages attained thereby will be readily understood by those skilled in the art.

30 In the accompanying drawing, Fig. 1 is a front face view of a bobbin-case embodying the invention. Fig. 2 is a perspective view of the base section of the bobbin-case. Fig. 3 is a diametrical section on the line 3—3, Fig. 1. Fig. 4 is a diametrical section of the cap-section only on the line 4—4, Fig. 1. Fig. 5 is a face view of a cap-section embodying the invention in modified form, 35 and Fig. 6 is a diametrical section on the line 6—6, Fig. 5.

The bobbin-case is, except as hereinafter described, constructed substantially in accordance with the disclosure of my said copending application. It comprises a cup-shaped base section 1 having the peripheral hook-bearing rib 2 and axial arbor post 3 notched or undercut at 4 to receive the locking tongue 5 of the latch-lever 6 which is pivoted on the pin 7 in the tubular axial 40 bobbin-supporting arbor 8 of the cap-section 9 of the bobbin-case. The cap-section 9 further comprises the circular end head 10 which carries the tubular arbor 8 and is cut-away or apertured to receive the latch-lever arm 6 substantially between the planes of its inner and outer faces, 12 and 13, respectively, when the latch-arm 6 is in closed or latching position.

In the form of the invention shown in Figs. 1, 2, 3 and 4, the end head 10 of the cap-section 9 is provided with a recess 14 of rectangular outline

to receive the coiled wire torsion-spring 15, the end leg 16 of which is received in the hole 17 in the latch-arm 6 and urges the latter from open position, shown in dotted lines in Fig. 3, to closed or full line position. The other end leg 18 of the 5 spring 15 rests in the groove 19 in the end head 10. Passing through the spring 15 is the arbor-pin 20 which is parallel to and between the planes of the inner and outer end head faces 12, 13. At its outer end the arbor-pin 20 is provided with a 10 lateral extension 21 facilitating its removal to release the spring 15 for replacement purposes. It will be observed that the spring 15 does not encroach upon the bobbin-receiving space within the bobbin-case, nor does it project from the outer 15 face of the end head 10 to impede the free passage of needle-thread loops about the bobbin-case.

In the modification of the invention shown in Figs. 5 and 6, the end head 10 of the bobbin-case is recessed at 22 to receive the leaf-spring 23 20 which is secured in the recess 22 by the screw 24 and is received at its free end in the hole 25 in the latch-arm 6 and urges the latter from open or dotted line position, Fig. 6, to closed or full 25 line position.

Like the coiled wire-spring 15, the leaf-spring 23 does not encroach upon the bobbin cavity within the bobbin-case nor project outwardly of the outer face of the bobbin-case. It does not impede the free passage of needle-thread loops about 30 the bobbin-case.

The foregoing specification is to be read in an illustrative sense and not in limitation of the invention which is susceptible of embodiment in various other forms than those illustrated, within 35 the spirit and scope of the invention.

Having thus set forth the nature of the invention, what I claim herein is:

1. A sewing machine bobbin-case comprising a cup-shaped base section having an axial arbor, 40 a cap-section having a circular end head and a tubular axial bobbin-supporting arbor, a latch-lever pivoted at a fixed point to said cap-section and releasably engaging said first-mentioned axial arbor, and spring means to bias said latch-lever from open position to arbor-engaging position.

2. A sewing machine bobbin-case comprising a cup-shaped base section having an axial arbor, a cap-section having a circular end head and a 50 tubular axial bobbin-supporting arbor, a latch-lever pivoted at a fixed point to said cap-section and releasably engaging said first-mentioned axial arbor, and spring means to bias said latch-lever from open position to arbor-engaging position.

tion, said spring being let into the end head of said cap-section.

3. A sewing machine bobbin-case comprising a cup-shaped base section having an axial arbor, a cap-section having a circular end head and a tubular axial bobbin-supporting arbor, a latch-lever pivoted to said cap-section and releasably engaging said first-mentioned axial arbor, a coiled wire torsion-spring let into the end head 10 of said cap-section to bias said latch lever to arbor-engaging position, and an arbor-pin for said torsion-spring.

4. A sewing machine bobbin-case comprising a cup-shaped base section having an axial arbor, a cap-section having a circular end head and a tubular axial bobbin-supporting arbor, a latch-lever pivoted to said cap-section and releasably engaging said first-mentioned axial arbor, a coiled wire torsion-spring let into the end head 15 of said cap-section to bias said latch-lever to arbor-engaging position, and an arbor-pin for said torsion-spring disposed parallel to the end head of said cap-section.

5. In a sewing machine bobbin-case having a cup-shaped base section with an axial arbor, a cap-section having a circular end head and a tubular axial bobbin-supporting arbor, a latch-lever pivoted to said cap-section and adapted to releasably engage said first-mentioned axial arbor, a coiled wire torsion-spring let into the end 25 head of said cap-section to bias said latch-lever to arbor-engaging position, and a removable arbor-pin for said torsion-spring disposed parallel to the end head of said cap-section and having 30 at its outer end a lateral extension facilitating its removal.

6. A bobbin-case cap-section having a circular end head formed with an aperture, a latch-lever

fulcrumed in said end head, a spring arbor pin disposed within said aperture, and a coiled wire torsion spring on said arbor-pin within said aperture, said spring having one end leg extended laterally of said spring coil and arranged to bear 5 upon said latch-lever.

7. A bobbin-case cap-section having a circular end head formed with a recess in its outer face, a latch-lever fulcrumed in said end head, and a spring disposed in said recess and having an end 10 arranged to bear upon said latch-lever in a direction transverse to the plane of said outer face.

8. A bobbin-case cap-section having a recessed circular end head and a tubular axial arbor, a latch-lever fulcrumed in said arbor and having 15 an operating arm received in said recess when in closed position, and a biasing spring recessed into said end head and having an end leg arranged to bear upon said operating arm in a direction toward said end head when said operating arm 20 is in open position.

9. A sewing machine bobbin-case cap-section having a disk-like end head and a tubular axial arbor normal to said end head, a latch-lever fulcrum-pin extending across said tubular arbor, a latch-lever fulcrumed on said pin, and a biasing spring bearing upon said latch-lever and received 25 in a recess in said end head.

10. A sewing machine bobbin-case cap-section having a disk-like end head formed with an aperture, a tubular axial arbor normal to said end head, a latch-lever fulcrum-pin extending across said tubular arbor, a latch-lever fulcrumed on said pin, and a coiled wire torsion-spring having 30 an extended end leg bearing upon said latch-lever, said spring being disposed in said aperture. 35

JOHN D. KARLE.
